Primary Examiner — Holly E Thurman*Assistant Examiner* — Leisha N Price(74) *Attorney, Agent, or Firm* — Quickpatents, LLC; Kevin Prince(57) **CLAIM**

The ornamental design for a differential reinforcement bracket, as shown and described.

DESCRIPTION

FIG. 1 is a bottom perspective view of a differential reinforcement bracket, showing our new design;

FIG. 2 is a top perspective view thereof;

FIG. 3 is a rear perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines showing a vehicle differential in FIG. 1 depict environmental matter and form no part of the claimed design. The broken lines showing a logo with text in FIGS. 2 and 4, and a bushing in FIG. 4, depict portions of the differential reinforcement bracket that form no part of the claimed design.
